PLLC

(57) **CLAIM**

The ornamental design for a display screen and mounting unit assembly for surgical instruments as shown and described.

DESCRIPTION

1. Display screen and mounting unit assembly for surgical instruments

1.1: Perspective

1.2: Front

1.3: Back

1.4: Top

1.5: Bottom

1.6: Left

1.7: Right

The present design is a main body used by mounting a skin perforating handpiece for skin transplantation, with a display on the upper part that indicates the perforation status, which is installed to be rotatable.

1 Claim, 7 Drawing Sheets
